(57) **CLAIM**

The ornamental design for a television receiver, as shown and described.

DESCRIPTION

FIG. 1 is a front perspective view of the television receiver showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a reference view showing the state of use that the front display part of the claimed design has been rotated 90 degrees vertically;

FIG. 9 is a reference view showing the state of use that the front display part of the claimed design has been rotated 90 degrees and raised upward vertically;

FIG. 10 is a front perspective view with the bottom back of the stand in an open configuration, in an alternate position;

FIG. 11 is a front view of FIG. 10;

FIG. 12 is a back view of FIG. 10;

FIG. 13 is a left side view of FIG. 10;

FIG. 14 is a right side view of FIG. 10;

FIG. 15 is a top plan view of FIG. 10;

FIG. 16 is a bottom plan view of FIG. 10;

FIG. 17 is a reference view showing the state of use that the bottom-back part of the body has been using as a stand and the front display part of the claimed design has been rotated 90 degrees vertically; and,

FIG. 18 is a reference view showing the state of use that the bottom-back part of the body has been using as a stand and

(Continued)

the front display part of the claimed design has been rotated 90 degrees, and then raised upward vertically. The broken lines depict portions of the television receiver that form no part of the claimed design.
